Des. 241,744

Patented Oct. 5, 1976

241,744

INSULATOR FOR ELECTRIFIED RAIL

Thomas E. Betscher, Cincinnati, Ohio, assignor to The Sperry Rubber & Plastics Co., Inc., Brookville, Ind.

Filed Dec. 4, 1975, Ser. No. 637,586

Term of patent 14 years

Int. Cl. D13—03

U.S. Cl. D26—10

FIG.1.

FIG.2.

FIG.4.

FIG.3.

FIG.5.

FIG. 1 is a perspective view of an insulator for electrified rail embodying my new design;

FIG. 2 is an enlarged top plan view thereof with a portion omitted for convenience of illustration.

FIG. 3 is a side elevational view thereof;

FIG. 4 is an end elevational view thereof; and

FIG. 5 is an bottom plan view thereof.

I claim:

The ornamental design for an insulator for electrified rail, substantially as shown and described.
